UNITED STATES PATENT OFFICE.

SAMUEL JUMP, OF SAN FRANCISCO, CALIFORNIA.

TENSILE-STRAIN-TESTING MACHINE.

SPECIFICATION forming part of Letters Patent No. 404,200, dated May 28, 1889.

Application filed February 6, 1889. Serial No. 298,892. (No model.)

To all whom it may concern:

Be it known that I, SAMUEL JUMP, of the city and county of San Francisco, State of California, have invented an Improvement in 5 Tensile-Strain-Testing Machines; and I here-
by declare the following to be a full, clear, and exact description of the same.

My invention relates to the class of testing-
machines; and my invention consists in the 10 novel arrangement and combination of parts
hereinafter described, and particularly point-
ed out in the claims.

The object of my invention is to simply and
accurately arrive at the strength of any ma-
terial by dead-weight. Its uses are, primarily,
15 for testing by such strain the strength of metal-
lic substances—such as iron or steel bars, wire,
springs, spring-balances, and ropes, whether
vegetable or metallic—it being also applica-
20 ble to organic substances, all of which can be
tested more accurately than by the known hy-
draulic appliances with less liability to error
in calculating the results, the dead-weight sys-
tem removing it practically beyond errors.

25 Referring to the accompanying drawings
for a more complete explanation of my inven-
tion, Figure 1 is a side elevation of my ma-
chine. Fig. 2 is a modification of the same.

A is a bed, to which, near one end, is bolted
30 the upright bracket B, consisting of two sep-
arated parts, between the tops of which is
mounted the rocking cross-head C, which car-
ries the clamp. This cross-head has on its
35 sides the pivot-pins c, which are journaled in
the top of the bracket sides, so that it may
rock on its pivotal centers. Through the
cross-head is made an aperture, c', in which is
fitted the clamp D, adapted to be operated
40 by a set-screw, d. Near the other end of the
bed A is bolted an upright bracket, E, be-
tween the sides of which at the top is pivoted
the elbow or bell-crank lever F. In the top
45 of the upright or short arm of this lever is
mounted the rocking cross-head G, with pivot-
pins g and receiving-aperture g'. In the cross-
head is the clamp H and the operating set-
screw h, the whole being adapted to operate
50 in a manner similar to the corresponding parts
in the bracket B.

55 To the horizontal or long arm of the lever
is connected the pendant I, on which the
weights W are carried.

J is the bar to be tested. Its ends are passed
through the apertures in the rocking cross-
heads C and G and are bound therein by the 55
clamps D and H, which are forced down upon
it by their respective set-screws. Weights are
then successively placed upon the pendant I
until the bar is fractured or has borne the
required amount of strain. The rocking cross- 60
heads by their movement conform to the
changing position of the lever and thereby
accommodate themselves to the bar being
tested in whatever position it may be drawn
or placed.

65 K is a screw having a head, k, and mounted
at its lower end in a fixed stand, L, the screw
being operated by a hand-nut, M, in the usual
manner of a lifting-jack or screw. This screw
is placed in position directly under the long 70
arm of the lever F, and as said arm comes
down under the increasing weights placed
upon its pendant the screw is run down by
hand to lie just under it without supporting
it. When the bar is fractured, the lever, in- 75
stead of falling with suddenness, is received
almost immediately upon the head of the screw,
and injury to the machine is thereby pre-
vented.

80 In Fig. 2 I show a slight modification of my
machine, in which the power-lever, instead of
being of an elbow or bell-crank shape, is
straight. Its fulcrum-pin (represented at O) is
nearer one end than the other, thereby giving
85 the necessary leverage. The bar to be tested
is placed in a vertical position, its lower end
being held firmly down by a suitable fixed
clamp or grip, as at P, and its upper end be-
ing connected with the short arm of the lever
90 by a clamp in a rocking cross-head mounted
in the end of the lever in the same manner
and for the same purpose as the cross-heads
heretofore described in connection with Fig.
1. The weights are hung from the long arm
95 of the lever, and as they are put on, the strain
on the bar increases until it either fractures
or has sustained the required strain. This
modified construction will preferably be em-
ployed in heavy work for breaking vertically.

100 In using the machine two fixed centers must
be taken on the piece to be tested by a "tram-
mel." Its exact measurements having been
ascertained, it is submitted to the strain of
the machine, weights being added until it is

broken, when the elongation is determined by the two fractured parts being put together, and another mark given by the trammel denotes the elongation.

5 Contraction of area is arrived at by measuring the fractured ends. The result is positive accuracy, and the tests can be made as easily as weighing articles on any platform or lever machine.

10 I am aware that testing-machines are known which operate by means of dead-weight acting through suitable levers, and I do not therefore claim such, broadly; but

15 What I do claim as new, and desire to secure by Letters Patent, is—

1. In a testing-machine, the combination of the upright bracket B, having in its top the pivoted or rocking cross-head, with adjustable clamp for receiving and holding one end of 20 the bar to be tested, the fixed bracket E, and pivoted elbow or bell-crank lever in said bracket and having one end adapted to re-

ceive the testing-weights, and the rocking cross-head in the other end of said lever and having an adjustable clamp for receiving and holding the other end of the bar to be tested, substantially as described.

2. In a testing-machine, the fixed brackets B and E, the rocking cross-head with clamp carried by bracket B, the elbow or bell-crank lever pivoted in bracket E and having one end adapted to receive the testing-weights, and the rocking cross-head with clamp in the other end of the lever, in combination with the vertically-movable or adjustable support 35 K under the lever and adapted to receive it instantly when the bar to be tested is fractured, substantially as described.

In witness whereof I have hereunto set my hand.

SAMUEL JUMP.
